UNITED STATES PATENT OFFICE.

MELANTHON J. BRIGGS, OF PHILADELPHIA, PENNSYLVANIA.

ELECTRIC FIRE AND BURGLAR ALARM.

No. 874,483.

Specification of Letters Patent.

Patented Dec. 24, 1907.

Application filed April 25, 1906. Serial No. 313,610.

To all whom it may concern:

Be it known that I, MELANTHON J. BRIGGS, a citizen of the United States, residing at the city of Philadelphia, in the county 5 of Philadelphia and State of Pennsylvania, have invented new and useful Improvements in Electric Fire and Burglar Alarms, of which the following is a specification.

This invention relates to a combined automatic electric fire and burglar alarm apparatus, and has been especially devised for use not only in protecting life and property from dangers of fires originating in an occupied building, boat or other place, or one where a 15 watchman is employed, but also for giving timely warning of an attempt of a burglar to enter a building or apartment.

The apparatus has a general use and application, and may be employed in residential, 20 factory, hotel, office or other buildings, and in some arrangements may coöperate with a section comprising a number of buildings, and under the latter circumstances be located at some station under surveillance of a watch- 25 man or attendant.

The apparatus is peculiarly adapted to the protection of buildings in rural districts destitute of either fire or police protection, and all species of water craft against serious fires 30 and loss of life resulting therefrom.

The improved apparatus gives the inmates of a building or watchman or other person timely warning of the exact location of a fire when it first starts and at a time when it can 35 be easily extinguished; and likewise notifies the occupants of a building as to what part of the latter may be subjected to burglarious attempts.

The apparatus has the advantage of being 40 wholly automatic in its operation when properly set, and further, in the day time or whenever desired the burglar alarm may be cut off by means of a switch without in the least interfering with the operativeness of the fire alarm circuits which are controlled 45 by an initial circuit closing means or thermostat which responds to abnormal heat in any compartment or portion of a building or boat where it may be disposed.

50 The apparatus in giving a fire alarm does so through the medium of both audible and visual signals, so that the burglar alarm portion of the apparatus will not in the least interfere with the fire alarm organization there-

of when included with the other circuits, 55 owing to the operation of the visual signals which will at once notify an observer that the signal is for fire and the location of the fire, and an abnormal heat in any part of a building or boat can be readily determined 60 from an annunciator also included in the apparatus.

When the burglar alarm and fire alarm are set for operation, or the apparatus arranged so that both will operate, either one or both 65 may be actuated without interference of the fire alarm with the burglar alarm or vice versa.

The signal for the burglar alarm is entirely different from that given for fire, and in such 70 case the indicator on the annunciator relates to the burglar section which is entirely different from the section of the same number when indicated in connection with a fire alarm.

75 In the drawing, Figure 1 is an elevation of a supporting means showing the improved apparatus arranged thereon. Fig. 2 is a diagrammatic view illustrating the circuits together with the main instrumentalities employed in giving the signals. Fig. 3 is a detail sectional view of one of the thermostats or initial circuit controlling means. Fig. 4 is a sectional view of a circuit controlling device forming the initial circuit controlling means 80 for the burglar alarm portion of the apparatus. 85

Similar characters of reference are employed to indicate corresponding parts in the several views.

90 It is preferred that the apparatus be supported by a suitable board or backing 1, though the same may be otherwise arranged, and the main elements include an electric bell or gong 2, an annunciator 3, a smaller bell or gong 4, incandescent electric lamps 5, a battery 6, and switches 7 and 8. All the parts just mentioned are of the usual or well known construction and may be obtained in the market in condition for assemblage to complete the organization of electric elements 100 embodying the features of the invention. The electric bell or gong 2 is very much larger than the electric bell or gong 4, and both of these bells or gongs will always ring or sound for a fire alarm, but only the smaller bell or 105 gong 4 rings for the burglar alarm. As both electric bells or gongs ring in the event of fire, with a prolonged operation, the difference in

tone of the two bells under these circumstances will be advantageous in calling attention of a watchman or other person to the fact that there is a fire in some part of a building in which the apparatus is located, in the event of the watchman or attendant being at the time at a distance from and unable to observe the visual signal which comprises the incandescent lights 5 and 5^a and the annunciator 3.

The only part of the apparatus which will need repair and attention under normal conditions is the battery 6, and this will be conveniently disposed to render it readily accessible. (Fig. 2). The larger electric bell or gong 2 is included in the main circuit with the battery 6, said circuit consisting of a wire 9 leading from one pole of the battery to the switch 7 and from the latter to one terminal 15 of the magnet devices of the electric bell or gong 2. From the opposite terminal of the said magnet devices, a wire 10 connects with a binding post 11, and from this binding post a section wire 12 extends any suitable distance 20 away from the apparatus and connects with binding post 13 (Fig. 3) of a series of three thermostats 14, of what is termed for the purpose of illustration, a third section, or a certain compartment or part of a building, 25 boat or other place, and from the last of the series of thermostats 14 the said wire 12 continues on to and through another series of similar thermostats 15 in a second section or compartment, and from said thermostats of 30 the second compartment or section, this wire 12 continues through and connects with a series of thermostats 16 of a first section or compartment of a building or boat. Each of the series of thermostats also has another 35 wire 17 connecting with binding posts 18 (Fig. 3) thereof and also with a battery post 19, (Fig. 2), the latter being placed in electric communication with the battery 6 through the medium of a wire 20 attached to the other 40 element of the battery 6, the wires 17 and 9 representing respectively either the positive or negative elements of the said battery.

The annunciator 3, which as shown is arranged for giving a visual signal from either 45 one of three compartments or three different sections, is included in a circuit (Fig. 2) consisting of wires 21, 22, 23 and 24, the wires 50 24, 23 and 22 connecting with the wire 21 and with the indices or drops of the annunciator, as shown by Fig. 2, and the wire 21 also connects with one extremity of the magnet of the smaller bell or gong 4, and from the opposite extremity or the terminal of the latter magnet a wire 27 runs to the wire 9. 55 The lamp circuit includes a wire 26 connecting with the wire 9 and the two lamps 5, a wire 25 being interposed between the two lamps. This lamp circuit is also coupled by 60 means of a wire 30 to the wire 10 so as to in-

clude the larger electric bell or gong 2 and 65 also complete the circuit with respect to the battery 6.

The wire 22 connects with the binding post 36, and from said binding post a wire 37 runs to and connects with the thermostats 70 14, but does not continue beyond the latter and forms a section wire for controlling the operation of index No. 3 of the annunciator, when the said thermostats 14 close the circuit in view of abnormal heat in the compartment or section of a building or boat in which they may be located. The thermostats 15 have a section wire 40 attached thereto and said thermostats are intended to be located in a second section or room of a 75 building or boat and to this wire 40 a wire 39 is connected and also to a wire 34 attached to a binding post 35 with which the wire 23 is also in electrical connection. From the thermostats 16 located in the first section or 80 room of a building or boat a section wire 41 runs to a binding post 42 and with the latter binding post the wire 24 of the annunciator circuit also connects.

The burglar alarm circuits include a binding post 31 from which a wire 32 runs to the switch 8, and from the latter switch said wire 32 continues to the battery post 19. From the post 31 a wire 33 continues outwardly any distance from the apparatus as a feeder 90 or continuation of one of the battery elements and passes through all the compartments or sections of the building where the apparatus is disposed for operation. The terminal of this wire 33 as shown in the diagrammatic view, Fig. 2, represents the first 95 section or room in which the burglar alarm controlling device may be located, and coöperating therewith is a section wire 43 which connects with wire 41 attached to a binding 100 post 42, and to this binding post the wire 24 is connected as hereinbefore set forth. This circuit will control the operation of the No. 1 index or drop of the annunciator and when the said circuit is closed the annunciator will 105 give indication that an attempt is being made to enter a section or compartment of a building which may be designated the first section. The wire 22 connects with the binding post 36 as heretofore set forth and by 110 this means the No. 3 index of the annunciator will be operated when the circuit is closed by the burglar alarm circuit controlling device which will be hereinafter set forth. Connecting with the wire 37 is a wire 38 which 115 coöperates with the wire 33 and connects with the burglar alarm controlling device in the third section. The burglar alarm circuit in section or room No. 1 is made through the medium of a wire 43 connecting with the 120 wire 41 and coöperating wire 33, both wires 43 and 33 being attached to the burglar alarm controlling device. A wire 34 extend-

ing from the binding post 35 and connected with the annunciator drop No. 2 extends through the second section or compartment of the building and coöperates with the wire 5 33 to form the burglar alarm circuit for that section.

The apparatus is shown as adapted for use in three sections or compartments, but it will be understood that the apparatus may be 10 used in any number of compartments or sections by the addition of the necessary wires, thermostats, burglar alarm controlling devices and increase corresponding thereto in the number of annunciator indices or drops.

15 The preferred form of thermostat used is shown by Fig. 3 and embodies a metallic diaphragm 44 coöperating with the terminals of the binding posts 13 and 18 which project in operative relation thereto, the periphery of 20 the said diaphragm being attached by the wire 17 through the binding post 19 with the battery 6. When the diaphragm expands the circuit is completed through the binding posts 13 and 18 and the connections therefor 25 in all the thermostats of each section or compartment, a number of these thermostats being used by preference to insure the operation of the apparatus and a quick response to abnormal heat condition that may be present 30 in different portions of a compartment or section. These diaphragms 44 of the thermostats will be made responsive to different degrees of heat so that one series of the same may be placed in a room having a normally 35 higher temperature than another room where there is a second series responding to another abnormal temperature and so on throughout the whole thermostat organization so as to render the apparatus practical and definite 40 as to the actuation of the signals, both audible and visual. In other words, the apparatus is so arranged that the signals will respond only when there is the actual existence of fire.

45 The burglar alarm circuit controlling device is shown in detail in Fig. 4 and includes in its structure a spring pin 45 held in a block 46 and working through a face plate 47 of metal, the terminals of the wires of the 50 several burglar alarm sections heretofore specified being connected to the said plates 47 and the pin, the latter when released moving outwardly and completing the circuit. This burglar alarm controlling device is inserted 55 in a door jamb or window frame in such manner that when the door or window is closed the pin will be forced inwardly and the circuit including the controlling device well remain open. As soon as the window 60 or door is opened by a burglar or in an irregular manner, the pin is released and the circuit closed.

It will be observed that two line wires of the fire alarm circuits and one line wire of

the burglar alarm circuits extend throughout the entire building, boat or other place in which the apparatus may be installed. In other words, one wire is common to all the circuits and may be properly termed the feed wire translating the effect of one of the 70 battery elements. Changes may be adopted within the purview of the invention to adapt the apparatus for installation in particular places or locations.

It will be noted that the binding post 19 is 75 directly connected by the wire 20 with the positive side of the battery 6. The binding post 31 is connected with binding post 19 by wire 32 to switch 8 and by wire 32 to binding post 19. All other binding posts 11, 36, 35 80 and 42 are connected with the negative side of the battery, ultimately by wire 9 through switch 7. Fire gong 2 is operated by wire 10 from binding post 11 to one terminal of its magnet devices and from the opposite terminal by wire 9 to battery 6. The lamp circuit includes wire 10 connected to wire 30 extending to lamp 5 and wire 25 connecting lamp 5 with lamp 5^a from which wire 26 connects with wire 9, running to battery 6. The 90 indicator No. 3 on the annunciator 3 is operated from binding post 36 by wire 22 connected with its drop or indicator, connected with wire 21 running to one extremity of the magnet of the small bell 4 and from 95 the opposite terminal of said magnet by wire 27 to wire 9. The indicator on said annunciator No. 2 is operated from binding post 35 by wire 23 running through its drop or indicator and connected with wire 21, and thence 100 as above indicated. The indicator on said annunciator No. 1 is operated from binding post 42 by wire 24 running through its drop or indicator and connected with wire 21, and thence as above indicated. From the bat- 105 tery binding post 19 a wire 17 together with a wire 12 from binding post 11 extend together through every section of the building or boat protected with the fire alarm and are each connected with every thermostat in the 110 building. Wire 17 is attached to the binding post 46 (Fig. 3) which connects with the periphery of the diaphragm 44 (Fig. 3) of each thermostat; and wire 12 is attached to binding post 13 (Fig. 3) of each thermostat. 115 Upon the drawings (Fig. 2), said wires are shown as attached to thermostats 14, 15 and 16 in third, second and first sections of building.

Section wire.—From binding post 36, a 120 section wire 37 extends through thermostats 14, 14 and 14 of the third section and is attached to binding post 18 (Fig. 3) of each thermostat. From binding post 35 a wire 39 extends through thermostats 15, 15, 125 15 of the second section and is attached to binding post 18 (Fig. 3) of each thermostat. From binding post 42 a wire 41 extends

- through thermostat 16, 16, 16 of the first section and is attached to binding post 18 of each thermostat. Thus when the abnormal heat applied to the diaphragm of any thermostat 5 stat causes expansion thereof sufficient to close the circuit at that point, the current not only causes the sounding of the fire gong 2 and the illumination of the lamps 5, 5^a through wire 12 to binding post 11, but the current through the section wire causes the drop or indicator on the annunciator 3 to show the number of the section when the circuit is so closed and the small bell 4 adds to the alarm.
- 15 The burglar alarm circuit extends from binding post 19 through wire 32 and switch 8 to binding post 31. From binding post 31 a wire 33 continues outwardly any distance from the apparatus as a feeder or continuation of one of the battery elements and passes through or to all rooms, doors, windows and other places protected and through all the different sections. From each section which may include several different contacts 20 another wire extends from the several contacts therein to the binding post that controls or operates the number thereof on the annunciator 3.

On the drawing, (Fig. 2), the house wire 33 30 extends throughout the entire burglar alarm system as shown. Section wire 38 for the third section extends from the contact or contacts in that section and connects with wire 37 which connects with binding post 36 35 and operates the indicator of No. 3 on the annunciator 3, and thence through small bell 4 as heretofore shown in the action of fire alarm. Section wire 34 for the second section extends from the contact or contacts 40 on that section to binding post 35 which operates the indicator No. 2 of the annunciator, and thence through small bell 4 as hereinbefore specified. Section wire 43 for the first section extends from the contact or contacts 45 in that section to wire 41 which connects with binding post 42 controlling or operating the indicator No. 1 on the annunciator, through wire 24 and thence through small bell 4 as before described.

50 What I claim is:

1. In an apparatus of the class set forth, the combination with audible and visual signals, the visual signals including electric incandescent lights, and an annunciator, of a battery or other source of electrical generation, a plurality of independent circuits each controlling some of the signals and arranged to extend through different sections of a building, boat or other place to give distinctive fire and burglar alarm indications in addition to, and independent of the annunciator, one conducting member of the fire and burglar alarm circuits extending continu-

ously throughout the whole series of sections and connecting with a common lead from the 65 battery, and automatically operating circuit controlling devices in both the fire and burglar alarm circuits.

2. In an apparatus of the class set forth, the combination of audible and visual signal 70 devices, a source of electrical generation, normally open circuits controlling the said audible and visual signal devices independently and arranged in sections, and automatic circuit closing devices arranged in 75 said circuits, some of which are operative by differences in temperature to close the circuits of the several sections.

3. In an apparatus of the class set forth, the combination of a plurality of signal 80 devices of different types, a source of electrical generation, circuits including the said devices and arranged in sections, the signal devices being operative to indicate both fire and burglar conditions and capable of individual or simultaneous operation, and automatic circuit closing devices included in the several sections, some of which devices are operative by variations in temperature.

4. In an apparatus of the class set forth, 90 the combination with a plurality of audible signals, visual signals, a source of electrical generation, circuits including the said signals and source of electrical generation, all of the audible signals being operated to give 95 a fire alarm, and one signal being operated to give a burglar alarm, and means for automatically closing different portions of the circuits to designate the location of a fire or the attempt of a burglar to enter a building 100 or other place.

5. In an electric signaling system, a plurality of groups of juxtaposed signals, each group comprising a plurality of signals of a different type from any other group, circuits 105 and a common battery for operating said signals, and means for actuating one or more signals of each type, simultaneously.

6. In an automatic electric fire alarm system, a series of thermostats, one wire connecting said thermostats with one signal device, a second wire connecting said thermostats with a second signal device, a battery, a third wire extending through the thermostats, and acting as a common return for the 115 other two wires, a fourth wire connecting therewith, and circuit closing devices responsive to burglar conditions located between this fourth wire and an extension of the first wire.

7. In an electric automatic fire alarm system, a plurality of groups of thermostats, a common two wire circuit extending to all of said thermostats and connecting with a battery and a signal device, and a plurality of 125 other wires, one extending to each group of

thermostats, and each connecting its own group of thermostats directly with the battery through an independent signal device.

8. In a combined automatic electric fire and burglar alarm system, a normally open two wire circuit, circuit closers therein responsive to fire conditions, a third wire forming with one of the first mentioned wires a second normally open circuit, circuit closers

therein responsive to burglar conditions, and 10 a distinctive signal device in each circuit.

In testimony whereof, I affix my signature in presence of two witnesses.

MELANCTHON J. BRIGGS.
